UNITED STATES PATENT OFFICE.

LLOYD WILSON, OF KESWICK, ENGLAND.

GAS-BURNER.

1,350,051.

Specification of Letters Patent. Patented Aug. 17, 1920.

Application filed April 7, 1917. Serial No. 160,485.

To all whom it may concern:

Be it known that I, LLOYD WILSON, a subject of His Majesty the King of England, and resident of Keswick, in the county of 5 Cumberland, Kingdom of England, have invented certain new and useful Improvements in Gas-Burners, of which the following is a specification.

This invention relates to improvements 10 in gas burners.

The primary object of the present invention is to provide a burner in which a common means of adjustment is provided for simultaneously regulating the gas and the 15 primary air supply. The said adjustment means may conveniently comprise an axially slideable piston valve, or a screw or rack operated sleeve valve as may be preferred.

20 The invention is hereinafter described with reference to the accompanying drawings in which:—

Figure 1 is a sectional side elevation of one form of construction;

25 Fig. 2 is a partial sectional side elevation illustrating a slightly modified construction; and

Fig. 3 is a detail view illustrating a modified form of controlling mechanism.

30 As shown and in one practical construction shown in Fig. 1 the body *a* of the burner is formed of tubular section and tapered toward its delivery end *a'* where it is provided with the secondary air ports *b*.

35 The gas is supplied to the outer end of the burner by way of an angular connection piece *c* and the primary air is supplied to the burner partly by means of a central or axial arranged tube *d* which projects 40 through the aforesaid gas inlet connection piece *c* and partly by means of a series of annularly arranged inlet ports *e* formed around the inlet end of the burner tube *a*.

These ports *e* are adapted to be adjusted in 45 area by means of an adjustable ring *f* which may be rotatably or axially movable in relation to the burner tube *a*. The common regulating valve for controlling the gas and the primary air is in the form of a hollow

50 piston *g* which works axially or rotatably, or both axially and rotatably inside the gas inlet connection *c* and controls the gas inlet and also the annular series of primary air inlets *e*. This hollow piston valve *g* is 55 freely connected by means of a boss *h* on its end to the central air tube *d* by the provi-

sion of a pair of spaced collars *i j* thereon. The external surface of a part of this tube *d* is screw threaded as shown at *k* and works through a threaded boss or cap *l* which 60 closes or forms the end of the burner and rotation of the tube *d* and axial movement of the valve *g* is effected by means of a hand wheel *m* provided at its outer end. A suitable form of valve *n* may, as shown, be provided to control the portion of the primary air passing up the tube *d* and also a valve *o* may, as shown, be provided to control the secondary air ports *b*. Where the central air tube *d* is not used a solid spindle would 65 be employed in its place. The tube *d* or the spindle, may also if desired be operated by means of a rack *p* and spur wheel *q*, as shown in Fig. 3, instead of the screw adjustment *k l* previously described. 70

In another slightly modified arrangement of the common regulating means a valve in the form of a screw threaded sleeve *g'* may be provided as shown in Fig. 2 which works on the outside of the gas inlet connection piece 80 *c* and engages with a screw thread cut in a cap *r* on the end of the burner tube *a*. In this construction the inner end of the sleeve *g'* would be formed as at *g''* to co-operate with the flared or funnel shaped inner end *d'* of the central tube *d* or spindle to regulate the gas supply and with a ring *s* of cone or other shape to regulate the primary air supply entering the ports *e*. The aforesaid ring *s* may conveniently be 85 adjustably mounted within the burner tube by suitable means such as by the provision of bolts or set screws *t* moving in longitudinally disposed slots *u* formed in the said burner tube *a* so as to control the series 90 of air ports *e* and also to vary its own position in relation to the flared or funnel shaped end *d'* of the central tube *d* or spindle and the inner end *g''* of the slideable valve sleeve *g'*. The sleeve *g'* is adapted to be 100 adjusted by means of a hand wheel *m'* provided on the outer end of the sleeve *g'*.

What I claim is:—

1. A gas burner for furnaces comprising in combination a tubular body portion having an inlet therein for the supply of air, an inlet for the supply of gas, an axially adjustable sleeve valve for simultaneously regulating the supply of air and gas and independent means for controlling the air inlet, substantially as described. 105

2. A gas burner comprising a tubular

body portion provided adjacent its outer end with a plurality of annularly arranged primary air inlets, a lateral inlet port for the supply of gas, a sleeve valve slidably mounted in said body portion and common to the inlet ports, and a rotatable means extending through the outer end of said body portion co-operatively connected to the sleeve valve to adjust the same axially for simultaneously regulating the supply of air and gas.

3. A gas burner for furnaces comprising in combination a tubular body portion having an inlet therein for the supply of air and an inlet for the supply of gas, an axially adjustable sleeve valve for simultaneously regulating the supply of air and gas and fixed adjustment means for regulating the relative proportions of the air and the gas supply, substantially as described.

4. A gas burner for furnaces comprising in combination a tubular body portion having inlet ports therein for the supply of primary air, means for controlling the opening of the said ports, an inlet port for the supply of gas, a common axially adjustable sleeve valve for simultaneously regulating the supplies of primary air and gas, and inlet openings in the tubular body portion at its delivery end for the supply of secondary air substantially as described.

5. A gas burner for furnaces comprising in combination a tubular body portion hav-

ing an inlet near its outer end for the supply of gas, inlet ports for the supply of primary air, a hollow sleeve valve having a port therein, and formed to co-operate with the gas inlet port and with the air inlet ports so as to simultaneously regulate the air and gas supplies, a screw threaded spindle in engagement with a threaded part of the body of the burner, a hand wheel connected to the said spindle and means for rotatably and operatively connecting the spindle with the said valve, substantially as described. 45

6. A gas burner for furnaces comprising in combination a tubular body portion having an inlet near its outer end for the supply of gas, inlet ports for the supply of primary air, a hollow sleeve valve having a port therein, and formed to co-operate with the gas inlet port and with the air inlet ports so as to simultaneously regulate the air and gas supplies, a hollow centrally arranged tube for the supply of additional primary air, means for connecting the tube to the adjustable hollow sleeve valve, and means for moving said tube in an axial direction relative to the body of the burner substantially as described. 50 60

In testimony whereof I have hereunto signed my name.

LLOYD WILSON.
